(57) **CLAIM**

The ornamental design for a rotatable mount assembly between holster and plate, as shown and described.

DESCRIPTION

FIG. 1 is a front elevational view of a rotatable mount assembly between holster and plate according to our invention, the broken lines illustrating the holster and plate and not forming parts of our invention;

FIG. 2 is a left side elevational view thereof;

FIG. 3 is a right side elevational view thereof;

FIG. 4 is a front side elevational view thereof;

FIG. 5 is a rear side elevational view thereof;

FIG. 6 is a bottom side elevational view thereof;

FIG. 7 is a top side elevational view thereof;

FIG. 8 is a view similar to FIG. 4 and showing the left side portion rotated 90°;

FIG. 9 is a view similar to FIG. 5 and showing the left side portion rotated 90°;

FIG. 10 is a view similar to FIG. 6 and showing the left side portion rotated 90°;

FIG. 11 is a view similar to FIG. 7 and showing the left side portion rotated 90°;

FIG. 12 is a view similar to FIG. 8 and showing the left side portion rotated 90°; and,

FIG. 13 is a view similar to FIG. 9 and showing the left side portion rotated 90°.
